UNITED STATES PATENT OFFICE.

WILLIAM EVANS, OF UVALDE, TEXAS.

KEY-RING CLIP.

1,345,357.

Specification of Letters Patent.

Patented July 6, 1920.

Application filed October 15, 1919. Serial No. 330,693.

To all whom it may concern:

Be it known that I, WILLIAM EVANS, a citizen of the United States, residing at Uvalde, in the county of Uvalde and State 5 of Texas, have invented certain new and useful Improvements in Key-Ring Clips; and I do hereby declare the following to be a full, clear, and exact description of the invention, such as will enable others skilled in 10 the art to which it appertains to make and use the same.

This invention relates to new and useful improvements in key ring clips and has for one of its objects the provision of a device 15 of this character for attaching a key ring to a belt or some portion of a garment and which will prevent the key ring from becoming detached when the wearer is occupying a sitting position as is frequent with 20 clips of the well known type now on the market.

Another object of this invention is the provision of a key ring clip of the above stated character, which shall be simple, durable and efficient and which may be manufactured and sold at a comparatively low 25 cost.

With these and other objects in view as will become more apparent as the description 30 proceeds, the invention consists in certain novel features of construction, combination, and arrangement of parts as will be hereinafter more fully described and claimed.

35 For a complete understanding of my invention, reference is to be had to the following description and accompanying drawing, in which:—

Figure 1 is a side elevation partly in section of a key ring clip constructed in accordance with my invention, and illustrating the same applied to a belt.

Fig. 2 is an edge elevation of the same, illustrating the overlapping ends of the 45 clip.

Fig. 3 is a similar view of the other edge of the clip.

Referring in detail to the drawing, the 50 numeral 1 indicates as an entirety a clip consisting of loops 2 and 3. The loop 2 is of a smaller size than the loop 3 and is adapted to receive or have passed therethrough a belt 4 for attaching the clip to the wearer. The loop 3 is considerably larger than the

loop 2 and has an open portion to permit a 65 key ring 5 to be placed on the loop 3 for supporting keys thereon.

The clip 1 is constructed from a single length of resilient material, which material is first bent upon itself to form the 60 loop 2 and the ends are extended laterally of the loop 2 to form the loop 3. The end 6 of the material is tapered as illustrated at 7 and abuts a flat face 8 formed on the end 9 and which end is enlarged as illustrated at 65 10 and disposed slightly laterally of the end 6 so that a key ring can be readily inserted between the ends 6 and 9 for placing and removing a key ring from the loop 3. The end 6 is disposed downwardly while the end 70 9 is disposed upwardly when the device is applied to the belt 4. By having the end 6 disposed downwardly a comparatively smooth face is provided to the loop 3 so that after the ring has been applied onto the 75 loop an upward movement of the ring caused by a person occupying a sitting position will not catch or pass between the ends 6 and 9. To remove the key ring from the loop 3, a downward and lateral pull is made 80 upon the ring causing the same to pass between the ends 6 and 9 and the replacing of the ring on the loop is accomplished in the same manner.

While I have shown and described the 85 preferred embodiment of my invention, it will be understood that minor changes in construction, combination and arrangement of parts may be made without departing from the spirit and scope of the invention as 90 claimed.

Having thus described my invention, what I claim is:—

1. A key ring clip comprising a loop member adapted to receive a belt, a second loop 95 member formed integrally with the first loop member and having its ends overlapped to receive a key ring.

2. A key ring clip comprising a single length of material bent upon itself to form 100 an elongated loop adapted to receive a belt, the ends of said material being disposed laterally of the loop and in overlapping relation to form a second loop adapted to receive a key ring.

3. A clip comprising a single length of material bent upon itself to form an elongated loop adapted to receive a belt, the 105

- ends of said material extending laterally of the loop and in overlapped relation to form a second elongated loop of a larger size than the first named loop for receiving a key ring, 5 the downwardly extending end of said material being tapered and the upwardly extending end being flattened and enlarged, said enlarged end being disposed laterally of the other end to permit the easy insertion

of the key ring between the ends of the material.

In testimony whereof I affix my signature in presence of two witnesses.

WILLIAM EVANS.
